UNITED STATES PATENT OFFICE.

CHARLES FAGO, JR., OF WINTHROP HARBOR, ILLINOIS.

TOY.

Application filed March 22, 1921. Serial No. 454,391.

To all whom it may concern:

Be it known that I, CHARLES FAGO, Jr., a citizen of the United States, residing at Winthrop Harbor, in the county of Lake and 5 State of Illinois, have invented new and useful Improvements in Toys, of which the following is a specification.

This invention relates to toys and has for an object the provision of a toy of the whirling type being capable of rotation in opposite directions by the action of a cord, the momentum provided acting to rewind the cord so that the operation of the toy may be indefinitely continued. 10 Another object is the provision of a toy of this character which includes a rotatable shaft and is provided with a novel form of bearing in which the shaft may rotate, the construction being such as to form from a 15 single piece of wire, a handle engaging arm, spaced bearing loops and a cord receiving or guiding loop.

With the above and other objects in view, the invention further includes the following 20 novel features and details of construction, to be hereinafter more fully described, illustrated in the accompanying drawings and pointed out in the appended claims.

In the drawings:—

30 Figure 1 is a side elevation of a toy constructed in accordance with the invention.

Figure 2 is a view at right angles to Figure 1.

Figure 3 is a section on the line 3—3 of 35 Figure 1.

Referring in detail to the drawings, wherein like characters of reference denote corresponding parts, the reference character 10 indicates a shaft, which has mounted on 40 each end balance elements 11 and 12, the former being shown as smaller than the latter. These balance elements may be of any desired shape or configuration, the purpose being to provide means whereby the shaft 45 may be rotated and the balance elements act to provide increased momentum.

The shaft 10 is mounted for rotation in a bearing which is formed of a single piece of wire. This wire is arranged to provide a 50 handle engaging arm 13, upon which is

mounted a suitable handle 14. Extending in opposite directions from the handle engaging arm 13 are divergent arms 15, which are bent at right angles and coiled to provide aligned bearing loops 16 within which the 55 shaft 10 is mounted. Extending from the bearing loops 16 is an eye 17 which provides a guide for a cord, the said eye being formed by coiling the wire centrally and forming spacing arms 18 which connect the eye 17 60 with the bearing loops 16. In forming the structure just described, the eye 17 may first be formed and the bearing loops 16 provided, whereupon the divergent arms 15 may be bent inward and have the extremities 65 thereof arranged in parallel contacting relation to form the handle engaging arm 13. A pin 19 extends through the shaft 10 upon one side of the bearing member and cooperates with the balance elements 11 to 70 prevent longitudinal movement of the bearing member upon the shaft.

In the operation of the toy, a cord is threaded through the eye 17 and has one end secured to the shaft 10, the latter may 75 then be revolved to wind the cord upon the shaft, whereupon a pull on the outer end of the cord will cause the shaft to rotate rapidly. After the cord has been entirely unwound from the shaft 10, tension upon said 80 cord is released and the accelerated momentum imparted to the shaft 10 by unwinding the cord, will cause the said cord to be rewound upon the shaft in an opposite direction, the cord may be given a pull to unwind 85 and permitted to rewind as previously described, this operation being repeated as desired, as will be readily understood.

The invention is susceptible of various changes in its form, proportions and minor 90 details of construction and the right is herein reserved to make such changes as properly fall within the scope of the appended claims.

Having described the invention what is 95 claimed is:—

1. A toy comprising a shaft, a balance element carried thereby, a handle, a bearing member extending from said handle, said bearing member being formed from a single 100

strand of wire bent centrally to provide a cord receiving eye, spaced bearing loops and a handle engaging limb.

2. A toy comprising a shaft, a balance element secured to each end thereof, a bearing member mounted upon the shaft, said member including spaced shaft receiving eyes, a

cord guide located intermediate the shaft receiving eyes and an arm extending radially from the shaft receiving eyes opposite the cord guide and a handle secured upon the arm.

In testimony whereof I affix my signature.

CHARLES FAGO, JR.
